UNITED STATES PATENT OFFICE.

JOSEPH EDWIN KOCHA, OF LINDEN, NEW JERSEY.

LUMBER DRIER.

Application filed November 20, 1925. Serial No. 70,331.

This invention relates to an apparatus for drying lumber, the general object of the invention being to provide means whereby green lumber can be quickly dried ready for the market so that it need not be piled and allowed to dry by natural process.

Another object of the invention is to cause the lumber to take a circuitous path through a drying chamber so that the lumber will be subjected to the drying action for the maximum amount of time without coming to rest in the chamber.

A further object of the invention is to provide means for causing heated air to circulate through the drying chamber, with means for additionally heating the air by heating means within the chamber.

A further object of the invention is to subject the lumber just entering the chamber to the action of steam to facilitate its drying.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is an elevation of the apparatus.

Figure 2 is a vertical sectional view.

Figure 3 is a section on line 3—3 of Figure 2.

Figure 4 is a plan view of portion of a track for a conveyor chain, a portion of the chain being shown.

Figure 5 is a sectional view on line 5—5 of Figure 6.

Figure 6 is a sectional view on line 6—6 of Figure 5.

Figure 7 is a view of one of the heating elements.

Figure 8 is a section on line 8—8 of Figure 2.

Figure 9 is a section on line 9—9 of Figure 8.

Figure 10 is a section on line 10—10 of Figure 9.

Figure 11 is a sectional view through the steam valve.

In these views, 1 indicates a housing which forms the drying chamber. This housing is divided into a number of horizontal passages

by the floors 2, alternate floors having end extensions 2' at one end of the housing and the other floors having their extensions at the opposite end of the housing. Thus the floors 60 form a zigzag passage through the housing.

A plurality of horizontally arranged shafts 3 are journaled in each end part of the housing, these shafts being in alignment with the floors, with the shafts adjacent the extensions 2' being arranged between the extensions and the floors. These shafts carry the sprockets 4 which are spaced apart by the spacers 5 and the conveyor chains 6 pass over the sprockets. Each chain includes the rollers 7 which are spaced apart by the links of the chain and these rollers are adapted to engage the tracks 8 which are arranged above and below each floor. The drums formed by the sprockets and spacers practically fill up the space between the ends of the floors and their extensions. The tracks are so arranged that the upper stretch of one conveyor is arranged parallel to and adjacent the lower stretch of the next upper conveyor so that 75 the lumber will pass between the two parallel parts of the conveyors, with the weight of the upper conveyor thereon, and thus the lumber will be held flat and cannot buckle.

Short conveyors 9 engage some of the sprockets on the drums that are placed between the floors and the extensions and these short conveyors pass over small sprockets 10, each set of which is carried by a shaft 11 journaled in brackets 12 which are placed 80 adjacent the sprockets which are arranged in each space which connects a lower passage with an upper passage. These short conveyors 9 act to carry the lumber from a higher passage to a lower passage.

The shafts 3 at one end of the housing can be adjusted horizontally so as to take up slack in the conveyor chains. The ends of these shafts are carried by the blocks 13 which slide in the guideways 14 and are adjusted by the screw shafts 15 which pass through the nuts 16 fastened to the guideways. Thus by turning these shafts, the blocks can be moved in either direction to loosen or tighten the conveyor chains.

Coils 17 are arranged under each set of tracks, these coils being connected to a steam supply by means of the inlet pipes 18 and the steam exhaust through the outlet pipes 19. Of course, other means for heating the 105 interior of the housing can be utilized instead of the steam means.

Hot air is also supplied to the housing through the intakes 20 which are connected to a suitable source and this air, after passing along the passages of the housing will be carried from the housing by the exhaust fans 21 and 22. The fan 22 can be provided with a controlling valve 23, if desired.

The lumber in the top passage is subjected to the action of steam jets which come from

- 10 the nozzles 24, the drawings showing two rows of these nozzles for directing the steam downwardly upon the lumber and a single row 24' for directing the steam upwardly against the lumber. Each row is controlled
- 15 by a valve 25, the handle 26 of which is arranged in the path of the lumber so that the valve will be automatically opened against the action of a spring 27 connected with the handle, by the lumber as the lumber is carried along by the conveyors. As soon as the lumber passes the handle, the spring will return the parts to normal position and shut off the supply of steam. I may place one of these steam sprays in the passage next to
- 20 the top, as shown at 24''. Flaps 28 on the top of the housing and extending down to a point adjacent the top conveyor drums act to hold the steam in the top passage and this steam is exhausted by the exhaust fan
- 25 29. These flaps may be adjusted by the handles 30 on the exterior of the casing and the valve 23 can be adjusted by the handle 31. Thermometers 32 are provided for indicating the temperature within the passages.
- 30 35. The lumber is fed into the top of the housing upon the top conveyor by the conveyor 33 and the front row of shafts 3 are geared together, as shown at 34.

From the foregoing, it will be seen that the lumber fed into the top of the housing by the conveyor 33 will drop upon the top conveyor and after pushing by the front flap 28, will enter the top passage and be passed along the same by the conveyor. As the lumber strikes the valve handles 26, it will open the valves so that steam will be jettisoned upon the lumber. It will also come in contact with the heated air in said passage. The lumber finally strikes the rear flap 28 and pushes by the same and it will then pass over the rear conveyor drum and fall upon the short conveyor 9 which causes the lumber to pass along with the lower reach of the upper conveyor until it is engaged by the upper reach of the next lower conveyor. The lumber is then carried along the passage next to the top passage by the upper reach of the second conveyor and the lower reach of the first conveyor to the end of the second passage, where it is carried by the second short conveyor 9 to the third passage and this action continues until the lumber is discharged through the discharge opening 35. Thus the lumber follows a zigzag passage through the housing and throughout

its course is subjected to the drying action of the hot air entering the device, this air being further heated by the heating means within the housing. Thus the lumber will be thoroughly dried when it is discharged from the apparatus.

The air and steam laden air can be passed through a heater, such as shown in my application Serial No. 33,244, filed May 27, 1925, and then passed to the intakes. 75

The parts may be driven in any desired manner, the drawings showing a gear 36 on one of the front shafts 3 for driving the conveyors and the conveyor 33 has a shaft 33' of its upper driving means connected by 80 the chain and sprockets 37 with a shaft 9' of one of the short conveyors 9 so that said conveyor 33 will be driven with the other conveyors.

With this device, lumber can be quickly 85 dried as soon as it leaves the saw and sent to market with the least possible delay and without the handling now necessary in stacking lumber in yards to permit it to dry under natural conditions. 90

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:—

1. A drier of the class described, comprising a housing, a plurality of horizontal conveyors therein, tracks for portions of the conveyors for causing parts of the conveyors to travel parallel to each other and to press the material between them, means for feeding the material upon the upper conveyor, means for causing the material to pass from one conveyor to the next conveyor, means for heating the interior of the housing, means for subjecting the material on the first conveyor to the action of steam, such means including a valve and means for opening the same by the movement of the material on the conveyor. 100

2. A drier of the class described, comprising a housing, conveyor means therein for causing the material to pass in a zigzag path from the top of the housing to the bottom thereof, means for passing hot air through the housing, heating means within the housing and means for subjecting the material as it enters the housing to the action of steam, such means including a valve and means for opening the same by the movement of the material on the conveyor and means for automatically closing the valve after the material has passed it. 115

In testimony whereof I affix my signature.

JOSEPH EDWIN KOCHA.
